INDIRECT AIR HEATER

Herbert L. Grapp, Minneapolis, Minn.

Application April 4, 1938, Serial No. 200,047

2 Claims. (Cl. 257—177)

This invention relates to a heating device and particularly to such a device for heating a gas such as air. More specifically the invention relates to what is known as an indirect heater.

5 Such heaters are used to heat air to quite a high temperature and this heated air is used in various industrial drying and baking processes as in ovens where various objects have a coating dried thereon. Such heaters may also be used for space 10 heating. The type of the invention is that wherein the air is heated by a furnace which may use any suitable fuel such as gas or oil.

It is an object of the present invention to provide such a heater of simple, highly efficient 15 and inexpensive construction, and which can be easily assembled.

It is more specifically an object of the invention to provide such a heating device adapted to be disposed over a furnace and comprising a casing 20 having extending vertically therethrough a plurality of rows of flat narrow tubes through which the products of combustion from said furnace pass, means being provided for circulating air between said tubes in a circuitous path.

25 It is a further object of the invention to provide an indirect heater comprising a casing adapted to be disposed over a furnace having vertical side and end walls and novel top and bottom plates adapted to receive and support a 30 large number of tubes extending therebetween through which products of combustion pass and between which the air to be heated is circulated, said tubes being arranged for convenient cleaning.

35 These and other objects and advantages of the invention will be fully set forth in the following description made in connection with the accompanying drawings in which like reference characters refer to similar parts throughout the several 40 al views and in which:

Fig. 1 is a view in vertical section taken substantially on line 1—1 of Fig. 2;

Fig. 2 is a view partially in top plan and partially in horizontal section taken substantially on 45 line 2—2 of Fig. 1;

Fig. 3 is an end view of the heater as seen from the right of Fig. 1;

Fig. 4 is a partial plan view of one of the tube holding plates, some tubes being shown in horizontal section;

Fig. 5 is a section taken on line 5—5 of Fig. 4 as indicated by the arrow; and

Fig. 6 is a partial perspective view of one of the tubes used.

55 Referring to the drawings a device forming an

indirect heater is illustrated, the same comprising a casing designated generally as 10 which is adapted to be disposed above or over a furnace. In the embodiment of the invention illustrated a furnace is indicated having end frames formed of 5 vertical side angle members 11 and transversely extending angle members 12. A channel member 13 extends about the top of the furnace, vertical plates or wall members 14 being shown as disposed between angle members 11 and 12 and the 10 channel 13. The furnace is supported by vertical channel members 15 extending to channel 13, which support transverse angle members 16. Angle members 16 in turn support longitudinally extending bars 17 upon which are placed the 15 brick 18 forming the bottom of said furnace. Brick 19 form the end walls of said furnace and extend between members 16 and channel members 13. The furnace may have an inner lining material 20 and the furnace chamber has there- 20 in open brickwork 21. Some suitable fuel burner such as an oil or gas burner will be disposed within said furnace, one end wall of which will be provided with a suitable opening 19a through which the burner or fuel supply conduit may ex- 25 tend.

The furnace described is one of somewhat usual construction and per se forms no part of the present invention. Casing 10 has a bottom plate 10a which has side and end portions resting upon the channel members 13. A top plate 10b is provided which is a counterpart of plate 10 but reversely disposed and spaced above the latter a distance equal substantially to the height of casing 10. Casing 10 has a frame extending 30 thereabout at each end comprising the vertical angle members 10c and the top and bottom horizontal angle members 10d. Spaced vertical plates 10e extend across casing 10 and suitable insulating material 22 is disposed therebetween. 35 Casing 10 will also have suitable vertical side walls 10f supported by the vertical angle members 10c. Plates 10 and 10b have on their adjacent faces a plurality of rows of recesses 10g. These are shown as rectangular in form and are formed 40 by transversely extending projecting ribs 10h extending in parallel relation across plates 10a and 10b and the spaced ribs 10i which extend between and join the ribs 10h. Within each recess 10g is a projecting oblong rib 10j having closely ad- 45 jacent parallel sides and semi-cylindrical ends, each of said ribs 10j defining an opening 10k through its plate. It will be noted as shown in Figs. 2 and 4 that the ribs 10j are in staggered relation, said ribs in one row being disposed cen- 50

trally between the ribs in the adjacent row. Plates 10a and 10b each have a rib 10m extending thereabout at the side opposite the ribs 10j. A plurality of tubes 23 extend between plates 10 and 5 10b and have their ends respectively fitting over the ribs 10j in said plates. Suitable securing material 24 such as a heat resisting or asbestos cement may be disposed in the recesses 10g about the ends of tubes 23. Inner side plates 10g 10 extend between plates 10a and 10b having their lower portions secured in an outer groove 10p by suitable cement. The tubes 23 may be of seamless or other convenient construction but in Fig. 6 a portion is shown made of one piece of metal 15 bent into oblong form and having short projecting ribs 23a at one end of the tube which may be joined in any suitable manner as by welding. A plurality of horizontal partition forming plates 25 extend across casing 10 between the side walls 20 10f, said plates connecting with one end of casing 10. It will be noted that alternate partitions 25 have their ends spaced some distance from opposite ends of casing 10. Small curved plates 25a are disposed at the ends of plates 25 engaging 25 the end walls of the casing, one of said plates also being disposed at the lower rear corner of casing 10. An air inlet conduit 26 extends through the front end wall of said casing and thus through the plates 10e, the bottom of which 30 is substantially aligned with the uppermost partition 25. An outlet conduit 27 also extends through the front end wall of said casing, the top of which is substantially aligned with the lowermost partition 25. As shown in Fig. 3 conduits 26 35 and 27 extend substantially the full width of casing 10. A vent hood 28 illustrated as made from sheet metal extends over the top of plate 10b so as to enclose all of the openings 10k, the same having flanges secured to plate 10b by the screws 40 29. Said hood is provided with a suitable opening at its rear end for the outlet of the gases of combustion and the same is shown as having a handle 30 on the top thereof. A plate 31 may be secured at each side of casing 10 extending 45 throughout the length and height thereof spaced therefrom and having flanges at its edges secured by screws 32 to angle members 10d. Suitable insulating material 33 may be disposed between plate 31 and the sides of casing 10.

50 In operation the furnace comprising members 11 to 21 will be suitably fired and the hot products of combustion will pass upward therefrom through the tubes 23. These products of combustion will pass into the vent hood 28 and 55 will be led therefrom through a suitable conduit. Air will be blown into inlet conduit 26 and will pass into casing 10 and between the tubes 23 above the uppermost partition 25 to the rear end of the casing and will return below said partition 60 and above the next adjacent partition 25 to the front end of casing 10 when it will again travel toward the rear end of casing 10 between tubes 23 above the lowermost partition 25 and will then return below said lowermost partition to and 65 through a discharge conduit 27. The air will be directed by conduit 27 to the desired point of use. It will be noted that the air cannot take a straight path through the casing 10 between tubes 23 but must change its course at each row of tubes due 70 to the staggered relation of said tubes. The tubes have a large contact surface for the air and the air is quickly heated to a high degree by travelling in contact with said tubes, said air being heated both by radiation and convection. It will 75 be noted that the air nearest the outlet conduit

27 encounters the hottest part of the tubes or the part which is heated by the hottest products of combustion. As stated, the large area of surface on the tubes and the arrangement thereof results in an efficient heating of said tubes and a very 5 efficient heating of air travelling thereabout.

From the above description it will be seen that I have provided an extremely efficient heating device and one that is quite simple in construction. The device is compact and the space within the 10 casing 10 is used to maximum efficiency. The tubes are simple in form and are easily made and assembled. An important feature of the heater is that the tubes can be very easily cleaned. By removing the vent hood 28 which is easily done, 15 a cleaning device can be moved vertically down through the tubes and the tubes thus cleaned of any deposit. The inner sides of the tubes are unobstructed and the cleaning can thus be easily and quickly accomplished.

20 The header plates 10a and 10b are made of a cast alloy having appreciable percentages of chromium and nickel. In practice the plates have been found to be very satisfactory when containing 1½ percentage each of chromium and 25 nickel. The cast plates are quite durable and do not tend to grow, that is to permanently expand and crack as a result of high temperature. The non-metallic packing or securing material 24 makes for easy assembly of the device and for 30 quick and convenient removal of a tube should this be necessary.

35 The device has been amply demonstrated in actual practice, found to be very successful and efficient and is being commercially made.

35 It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. An indirect heating device adapted to be 45 disposed over a source of hot gases of combustion having in combination, a casing having top and bottom plates, a plurality of rows of tubes extending between said top and bottom plates, said tubes having flat parallel sides, said plates having 50 openings therethrough aligned with the openings in said tubes and having grooves extending about said openings therein in which the ends of said tubes are disposed and high temperature resisting material in said grooves about said tubes for 55 holding the same in place whereby the ends of said tubes are protected from the hot gases passing therethrough and means for passing air longitudinally through said casing about said tubes.

2. An indirect heating device adapted to be 60 disposed over a furnace having in combination, a casing having insulated vertical side and end walls and a bottom plate overlying said furnace, a plurality of rows of tubes extending from said bottom plate, said tubes having flat parallel sides 65 and being very elongated in horizontal cross section, said tubes having their sides extending lengthwise of said casing, the sides of adjacent tubes being in close proximity, said bottom member having openings therethrough with which 70 said tubes align so that the hot products of combustion from said furnace rise through all of said tubes, a top plate over said tubes having openings with which said tubes align, the ends of said tubes being disposed in said top and bottom 75

plates respectively, an inlet conduit extending into said casing adjacent said top plate, a plate extending horizontally from the bottom of said conduit around said tubes to the opposite end of said casing, an outlet conduit at the end of said casing below said inlet conduit and adjacent said bottom plate, a plate aligned substantially with the top of said outlet conduit extending horizon-

tally about said tubes to the opposite end of said casing and a plate extending from the end of said casing opposite said conduits around said tubes to adjacent the end of said casing with which said conduits connect whereby air entering 5 said inlet will pass around said plates and said tubes to said outlet conduit.
